Patented Aug. 16, 1921.

Inventor:
Alexander Fischer Jr.
By Walter D. Murray
Attorney.

UNITED STATES PATENT OFFICE.

ALEXANDER FISCHER, JR., OF CINCINNATI, OHIO.

MOP.

1,387,644.

Specification of Letters Patent. Patented Aug. 16, 1921.

Application filed July 9, 1919. Serial No. 309,590.

To all whom it may concern:

Be it known that I, ALEXANDER FISCHER, Jr., a citizen of the United States of America, and a resident of Cincinnati, in the county of Hamilton and State of Ohio, have invented a new and useful Improvement in Mops, of which the following is a specification.

The object of my invention is a mop of a construction that is strong and easy to make.

In the accompanying drawing,

Figure 1, is a side elevation of a mop embodying my invention, part of the handle being shown broken away.

Fig. 2, is a view taken at right angles to Fig. 1, but showing the parts partly in cross section.

The mop embodying my invention comprises a handle A, cross pin B, wire loop D, staples E, E' and the mop head G.

The staples E, E' are driven into the end of the handle and are then turned down so that their ends project at diametrically opposite points beyond the edge of the handle.

The cross pin B in the course of manufacture of the mop has straight ends. The strands of the mop being held against the handle by wire loop D which is passed through the ends of the staples E, E' and

its ends drawn tight over the pin B and then 30 bent down. Then the ends of the cross pin B are bent over, as shown in the drawings.

All of the steps taken in the course of manufacturing my mop are simple and quickly and easily performed. The cross pin 35 and the staples maintain the wire loop firmly and centrally in position so as to hold the strands of the mop head firmly in place.

Having thus described my invention, what I claim is:—

In a mop the combination of a handle, bent staples having their ends disposed within one end of the handle and having that portion intermediate the ends extending beyond the handle, a U shaped wire loop having its ends extending through the staples, eyes formed on the end of the wire loop, a cross pin extending through the handle and through the eyes formed on the ends of the wire loop, and having its ends bent upon 50 itself to secure the wire loop, and a mop head mounted on the loop intermediate the ends thereof and being fixedly retained upon the end of the handle thereby.

In testimony whereof, I have hereunto 55 subscribed my name this 5th day of July, 1919.

ALEXANDER FISCHER, JR.
